United States Patent Office

Des. 176,112
Patented Nov. 22, 1955

176,112

HAT

Pearl Pauline Gaichel, San Francisco, Calif.

Application July 26, 1955, Serial No. 37,139

Term of patent 14 years

(Cl. D3—13)

Fig. 1

Fig. 2

Fig. 1 is a perspective view of a hat showing my new design; and

Fig. 2 is a top plan view thereof.

The drawing is lined for color.

I claim:

The ornamental design for a hat, substantially as shown and described.
